Fig. 3

Fig. 4

FIGURE 1 is a perspective view of a carrying handle for a refrigerant cylinder embodying my new design, with a refrigerant cylinder being shown in broken lines for illustrative purposes only;

FIGURE 2 is an enlarged top plan view;

FIGURE 3 is an enlarged front elevational view; and

FIGURE 4 is an enlarged side elevational view thereof.

I claim:

The ornamental design for a carrying handle for a refrigerant cylinder, substantially as shown and described.
